UNITED STATES PATENT OFFICE.

GEORGE E. B. WELLES, OF SAN FRANCISCO, CALIFORNIA.

CARBURETER.

1,358,686.

Specification of Letters Patent.

Patented Nov. 9, 1920.

Application filed September 11, 1918. Serial No. 253,514.

To all whom it may concern:

Be it known that I, GEORGE E. B. WELLES, citizen of the United States, residing at San Francisco, in the county of San Francisco, State of California, have invented a new and useful Carbureter, of which the following is a specification in such full and clear terms as will enable those skilled in the art to construct and use the same.

- 10 This invention relates to a carbureter of the type in which the fuel is heated before being taken into the explosion chamber of the gas engine, the object being to make a perfect mixture of the fuel and air where-
15 by the fuel will be completely burned to carbon dioxid, thereby preventing formation of carbon in the engine cylinders as well as increasing the power produced for a given amount of fuel.
20 The object of this invention is to produce a carbureter which will avoid the defects of maintaining a small amount of the liquid fuel at a certain level adjacent an inlet valve or control opening of small dimensions for
25 the passage of the fuel, which small opening is easily clogged and objectionable in many ways.

Another object of the invention is to produce a carbureter which will operate to supply the fuel to the incoming air without having the incoming air draw it by suction from a needle valve at a high rate of speed, which necessarily brings the globules of the liquid into contact with the air, and some of which do not fully vaporize unless the fuel is of the highest grade.

In the present invention, the oil fuel is furnished to the incoming air in amounts varying with the engine speed and independ-
40 ently of the air suction. The fuel supply well of the carbureter is further fed through a tube of adequate dimensions to prevent clog-
ging at a speed greater than the supply actually required, the surplus being returned
45 to the main oil tank through suitable con-
trol valves and return pipes, thereby making it possible to maintain the oil supply at any desired level.

Another object of the invention is to va-
50 porize the fuel before bringing it into con-
tact with the incoming air, the heat from the exhaust gases of the engine being used to heat a small body of the fuel in a suit-
able position from which the vapors escape
55 to the air passing to the engine.

Another object of the invention is to con-

vert the fuel from its liquid state by evapo-
ration and not by mere atomization to a rich dry gas by heat applied to the supply end of the carbureter after which it is mixed 60 with the heated air and passed to the engine to be exploded.

Other objects of the invention will appear as the description proceeds.

An embodiment of the invention is shown 65 in the drawings in which the same reference numeral is applied to the same portion throughout, but I am aware that there may be modifications thereof.

Figure 1 shows an end elevation of a por- 70 tion of an eight cylinder engine having this carbureter applied thereto,

Fig. 2 is a vertical sectional view through the carbureter,

Fig. 3 is a side elevation of the carbureter, 75 the lower portion being broken away for convenience of illustration,

Fig. 4 is a view in side elevation of the supply end of the carbureter showing the supply pipe and surplus fuel return pipe 80 with the levers for controlling the supply valves,

Fig. 5 is a view in elevation of a portion of the carbureter shown in Fig. 4 looking in the direction of the arrow on Fig. 4, 85

Fig. 6 is a view illustrating the manner of controlling the supply of air to the carbureter, and

Fig. 7 is a transverse sectional view of the carbureter showing the air supply pipes and 90 the vanes for mixing the hot air with the vaporized fuel.

The numerals 1 and 2 indicate the cylinder case of the engine, which cylinders are secured upon the base 3, and which cylinders 95 receive their explosive gases through the manifold 4; this manifold having a suitable throttle valve 5, therein to increase or diminish the supply of fuel to the engine as may be required. 100

The crank shaft 6 of the engine has the usual timing gear 7 in mesh with the cam shaft gear 8 which latter drives the gear 9 for the operation of the ignition apparatus, not shown and forming no part of the pres- 105 ent invention.

A suitable casing 10 incloses the gears and another casing 11 incloses a gear 12 on a shaft 13 for operating this carbureter, the front plate inclosing all of the gears just 110 mentioned is not illustrated since it forms no part of this invention.

There is shown at 14 a pipe leading from one of the exhaust pipes 15 which supplies the carburetor with hot air, and from which another pipe 16 leads the used hot gases to any suitable place of discharge. The carburetor is connected with the supply manifold by means of the flange 17 which is in turn secured to the flange 18 of the engine manifold. Below the flange 17 there is a split casing formed of the two parts 19 and 20, the latter of which has a bearing 21 for the shaft 13 which operates the pump for maintaining the desired level of the liquid fuel.

15 The casing formed by the two parts 19 and 20 is annular in shape and there is a boss 22 on the shaft 13 which carries arms 23 and 24 with beater blades 25, 26 revoluble in said casing, the object of said blades being to thoroughly mix the air and fuel prior to its passage to the engine.

25 The side 19 of the casing in which the beater blades rotate has a casing 27 cast thereon which extends axially away from the beater casing, and which supplies the air to the engine in such quantities as may be required, holes 28 being provided for that purpose, which holes are regulated by means of the band 29 surrounding the back of the 30 casing 27 or covering the holes 28 whenever necessary. The pipe 14 is connected by means of the flange 30 with the hot gas casing 31, and the pipe 16 is connected by means of the flange 32 with the bottom of 35 the hot gas casing 31. The hot gas casing 31 has a plurality of pipes leading from its periphery to the casing 34 within the casing 27, and said pipes have their outer ends covered or uncovered with a band 35 which 40 has holes to permit said pipes 33 to receive air when necessary.

45 The bands 29 and 35 have arms 36 and 37 attached thereto for their operation, see Fig. 6, and said arms are in turn provided with the links 38, 39 connected to slotted levers 40, 40' respectively, the position of the links with respect to the lever being adjusted by means of the pivot pins 42, 43, with which 50 said links are secured to said lever so that the amount of opening of one band with respect to the other can be adjusted as may be required.

55 The bands are each made up of two sections 29 and 29', 35 and 35' secured together by means of the flanges 29'' and 35''.

60 Within the shell 34 is another shell 45 which has a series of openings therein to assist in mixing the incoming gas and air, and within this shell there are secured a series of inclined vanes 46 to give the rotary motion to the atomized body of fuel fed to the air through the perforated drum 47 which lies within the cage formed by the plurality of vanes 46. The vanes are secured to and revolved by the spider 46'

supported by the shaft 13, and they are also connected at their opposite ends to a ring 46a.

65 The drum 47 is annular and surrounds the shaft 13 for a portion of its length, and has a connecting pipe 48 which extends up into the heating chamber 31 and connects with the top of the fuel supply pipe 49, the connection being so arranged, as indicated at 70 50, as to prevent any surge of liquid fuel from passing over into the pipe 48, such surge passing into the pipe 51 and back to the fuel reservoir.

75 At the back of the casing forming the heating chamber 31, there is a bearing 53 for the shaft 13 and immediately in the rear of that is a bearing 54 for said shaft which has a packing gland 54' to prevent the escape of the fuel. The bearing 54 is connected with and forms a part of the fuel well 55, which has the pipe 49 connected therewith, and which receives its fuel from the pipe 56, the excess fuel being returned to the tank through the pipe 57. There is an extension 57' of the pipe 57 which connects with the upwardly extending pipe 49, and which pipe is provided with a butterfly valve 58, the purpose of which is to increase or diminish the level of the fuel in 85 the pipe 49.

90 95 In order to further regulate the height of the fuel in the pipe 49 there is a butterfly valve 59 in the latter pipe which in conjunction with the valve 58 determines the amount of fuel subjected to the heat from the exhaust gases at any time. In this connection, it is to be noted that the dotted lines 60 indicate the normal fuel level, 61 indicates the level of the fuel when running under ordinary conditions, and 62 the level 100 of the fuel when a still more rapid vaporization thereof is required.

105 The shaft 13 is provided with a screw blade 63 which forms a well known form of pumping apparatus, and in order that it may be continually primed, the pipe 56 has a swinging check valve 64 therein.

110 Since it is intended to operate this carburetor independently of the rate of suction of the engine and by the heat of the engine 115 exhaust, it is necessary to provide means whereby the carburetor may be flooded with the fuel for starting purposes, and this is accomplished by means of the small valve 65 in the pipe 66 extending from the lower 120 portion of the pipe 49 to the lower portion of the pipe 48. The valve 65 is operated by means of the lever 69 and the valves 58, 59 are operated by means of the levers 70, 71 respectively, the position of these two levers and the valves with respect to each other being determined by means of the set screw 72 which is carried by the lever 71, and the end of which screw contacts with 125 the lever 70.

The throttle valve casing 5 has a shaft 74 extending therethrough upon which the throttle valve 75 is mounted. This shaft is journaled in a bracket 76 and in bearings 77, 5 78 in the throttle valve casing. Secured on the end of the shaft 74 adjacent the throttle valve is a hub 79 which has a boss 80 thereon carrying a cam 81. This cam is placed on the boss in such a position as to engage 10 the lever 82 when the throttle 75 is fully closed so that at that time said lever 82 (which is pivotally mounted on the bracket 83) will disengage the clutch 84 from the clutch 85, which is rigidly connected with 15 the gear 12 thereby releasing the shaft 13. This sliding clutch 84 is connected to rotate with the shaft 13 although it may slide thereon, and the spring 86 causes it to normally engage the clutch on the face of the 20 gear 12, a boss 87 carried by said shaft holding the spring 86 against the slideable clutch 84.

The shaft 74 is also provided with a lever 88 which may be connected with any suitable linkage extending to the driver's seat, 25 or to the engineer's position, as may be required, for opening and closing the main throttle.

The operation of the carbureter is as follows:—With the engine at rest and the carbureter cold, the fuel in the supply tank will stand at the level of the dotted lines 60.

Assuming the main throttle valve 75 to be closed it will be seen that the centrifugal 35 beam 63 will be at a stand still even though the crank shaft is rotated by hand or otherwise.

It is therefore necessary to open the valve 65 to permit a small quantity of the fuel, 40 usually for this purpose a very light gasoline, which may be permitted to enter the casing 47 for starting purposes, and after a small quantity has been allowed to run into the drum 47, the valve 65 may be closed. 45 The main throttle valve 75 is then partially opened, at which time the sliding clutch 84 will engage the clutch 85 on the face of the gear 12, thereby starting the pump upon the rotation of the said gear, and as the engine 50 is started, the fan blades will thoroughly mix the fuel with the incoming air. Of course at the time the throttle valve is partially opened, the other air supply openings are also partially opened, but the arrangement is 55 such that at low throttle openings all of the air must be taken through the openings in the band 35, and therefore all of the air at low throttle openings must pass inside the casing 34 thereby insuring a rich mixture 60 for starting purposes.

As soon as the engine starts, hot exhaust gases will pass through the chamber 31 and heat the fuel in the pipe 49, and the position of the two valves 58, 59 will be so arranged 65 as to keep the fuel supply at the proper level

to give off the necessary vapor to operate the engine, the oil standing normally under the average running conditions at the line 61, although should it be necessary the valves 58, 59 may be arranged so as to cause 70 it to stand normally at the top line 62 should the fuel be of such a nature as to require that amount of heating to properly vaporize it.

As soon as the engine is started, the supply of fuel to the drum 47 will be continuous, and as the vapor is fed thereto the revoluble blades 46 will thoroughly mix it with the air, and it will be again mixed when it passes into the casing 20 by the 75 blades 25, 26, which are provided with suitable large openings to insure perfect mixing of the air and fuel vapor. Upon a further opening of the main throttle with increasing engine speed, the hot air ducts 33 will be 80 further opened and the band 29 will open the cold air supply to furnish the additional amount of air required for the greater engine speed, the fuel in the meantime having been raised in the pipe 49 with the increased 85 engine speed so that the additional heat applied thereto will cause more vapor to be given off therefrom.

Now, assuming the carbureter installed in an automobile, if the machine is going down 95 a sufficient grade and the throttle closed, the fuel will run back into the tank because the pump 63 will be stopped and thereby prevent the formation of gas and loss of fuel. Upon the opening of the throttle, the 100 pump is automatically started and the carbureter again begins to generate vapor.

The principal advantage of this carbureter lies in the fact that it may be used for the purpose of vaporizing heavier fuels than 105 are ordinarily used and its flexibility, in that fuels of different vaporizing qualities may be used by it by simply altering the adjustment of the valves 58, 59 up to the capacity of the carbureter, which is determined by 110 the height of the pipe 49.

Having thus described my invention what I claim as new and desire to secure by Letters Patent of the United States is as follows, express reservation being made of permissible modifications.

1. In a carbureter, a fuel supply and a fuel return pipe, means to heat a portion of said pipe, means to elevate the fuel into the heated portion of said pipe, and a conduit 120 for leading the vaporized fuel into the air chamber of the carbureter.

2. In a carbureter, a fuel supply and a fuel return pipe, means to heat said pipe, means to raise the fuel in said pipe into the 125 heated portion thereof when the throttle valve is open and the engine running, a conduit leading from the heated pipe into the air inlet chamber to the carbureter, and mechanical means to mix the vaporized fuel 130

and air prior to its being taken into the engine.

3. In a carbureter, a fuel supply and a fuel return pipe, an inverted U-shaped pipe connected with said supply and return pipes, a pump for raising the fuel level in said inverted U-shaped pipe, valves for adjusting the level of the fuel in said pipes, a conduit leading from said pipes to the air inlet chamber of the carbureter, means to heat said pipes and the conduit leading to the air inlet to vaporize the fuel, and mechanical means for mixing the fuel and air prior to its being taken into the engine.

4. In a carbureter, a fuel supply and a fuel return pipe, an inverted U-shaped tube connecting said pipes, means to mechanically raise the level of the fuel in said inverted U-shaped pipe when the throttle valve is open and the engine running, means to heat said inverted U-shaped pipe, a conduit leading therefrom through the heating chamber to the air inlet chamber, air inlet pipes extending through said heating chamber, means to increase or diminish the area of the air inlets, and means to mechanically mix the vaporized fuel and air prior to its inspiration into the engine.

5. In a carbureter, a fuel supply and a fuel return pipe, an inverted U-shaped pipe connecting the two, means to heat a portion of the latter pipe, a rotary pump for increasing the fuel level in the inverted U-shaped pipe, valves for adjusting the fuel level in said pipe, a conduit extending through the heating chamber from said pipe to the air inlet chamber, other pipes extending through the heating chamber and forming means for heating the incoming air, mechanical means for mixing the vapor and air, and other auxiliary means for supplying additional air to the engine.

6. In a carbureter, an air inlet casing, a supply and return pipe connected with said casing, an inverted U-shaped tube connecting the two pipes, a heating chamber for heating a portion of said U-shaped tube, a conduit leading therefrom through the heating chamber to the air inlet chamber, air inlet pipes extending through the heating chamber, and mechanical means for mixing the vaporized fuel with the air prior to its inspiration into the engine.

7. In a carbureter, an air inlet casing, a fuel supply and a fuel return pipe connected with said casing, an inverted U-shaped pipe connecting the two latter pipes, a centrifugal pump for increasing the fuel level in the inverted U-shaped pipe, valves for changing the level of the fuel in said pipe, a conduit extending from the inverted U-shaped pipe into the air inlet chamber and terminating in a perforated drum, a smaller pipe connecting the inlet conduit and supply pipe below the normal fuel level where-

by the liquid fuel may be turned into the air inlet chamber for starting purposes, and means to mechanically mix the air after passing into the carbureter.

8. In a carbureter, a casing, two sets of openings therein, pipes extending from one of said openings to an interior casing, and a peripherally movable band adapted to increase or diminish the supply of air that is permitted to pass to the engine.

9. In a carbureter, an air inlet casing, fuel supply and fuel return pipes extending thereto, an inverted U-shaped tube connecting the two pipes, a conduit extending therefrom into the air casing, a heater casing surrounding a portion of the U-shaped pipe and the conduit extending into the air inlet casing, said conduit terminating in an annular perforated drum, and mechanical means for mixing the vaporized fuel with the air upon its admission to the carbureter.

10. In a carbureter, an air inlet casing, fuel supply and fuel return pipes extending thereto, an inverted U-shaped tube connecting the two pipes, a pipe extending from said U-shaped tube to the air inlet casing, means to raise the level of the fuel in said inverted U-shaped tube when the engine is running and the throttle open, means to heat a portion of the U-shaped pipe; a throttle valve and means whereby the fuel level will be reduced to an unheated portion of the U-shaped tube when the throttle is closed and the engine running.

11. In a carbureter, an air inlet casing, fuel supply and fuel return pipes extending thereto, an inverted U-shaped tube connecting the two pipes, a casing for heating said tube, a throttle valve, means to raise the level of the fuel in said tube to the heated portion thereof when the engine is running and the throttle open, a conduit extending from the inverted U-shaped tube in the air inlet casing, mechanical means for mixing the fuel vapor with the air, air inlet pipes extending through the heater casing and into the air inlet casing, said air inlet casing having other openings for the admission of air and two partially movable bands for covering and uncovering the air inlet openings.

12. In a carbureter, an air inlet casing, a fuel supply and a fuel return pipe extending thereto, an inverted U-shaped pipe connecting the two pipes, a conduit extending therefrom to the air inlet casing, a throttle valve, means to raise the level of the fuel in said inverted U-shaped pipe when the engine is running and the throttle open, and means whereby the fuel level will be lowered when the throttle is closed.

13. In a carbureter, an air mixing chamber, a fuel supply pipe, means to heat a portion of said pipe, a throttle valve, means to raise the fuel level to the heated portion of

the fuel pipe, means connected with the throttle whereby the fuel level will be raised when there is a demand for more fuel and lowered on a reduction in the fuel demand, 5 and a conduit for leading the vaporized fuel to the air mixing chamber.

14. In a carbureter, an air mixing chamber, a fuel supply pipe, means to heat a portion of said pipe, a throttle valve, means co- 10 ordinated with the throttle valve to raise

the fuel level in the heated pipe as the demand for fuel increases, a conduit for leading the vaporized fuel to the air mixing chamber, and mechanical means for further mixing the air and fuel.

In testimony whereof I have hereunto set my hand this 12th day of June, A. D. 1918.

GEORGE E. B. WELLES.

Witness:

Wm. J. COWAN.
